CLAIM

The ornamental design for combined computer mouse pad and mouse container, as shown and described.

DESCRIPTION

FIG. 1 is a perspective view of a combined computer mouse pad and mouse container showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof; and,

FIG. 8 is the perspective view embodying the utilization of combined computer mouse pad and mouse container in which the mouse is not comprised in my design.
